QUICK RELEASE FASTENER

Robert C. Legat, New Britain, Conn., assignor to
 The G. E. Prentice Mfg. Co., Kensington, Conn.,
 a corporation of Connecticut

Application July 20, 1949, Serial No. 105,743

2 Claims. (Cl. 24—205.11)

1

This invention relates to slide actuated fasteners and more particularly to fasteners provided with separable bottom stops whereby the stringers may be entirely separated.

Ordinarily the stringers of separable fasteners are disconnected by moving the slide downwardly or in a direction to disengage the locked fastener elements on the stringers until the slider comes into engagement with the separable bottom stops, whereupon the two stringers may be readily separated. Many situations arise however, particularly in the case of relatively long fasteners, where the element of time in opening a fastener becomes important or where it is inconvenient to open the fastener in the usual manner, either because of its extreme length or its location on the article. In order to take care of such situations, the art has heretofore devised fasteners which when fully closed, may be quickly opened by a lateral separation of the stringers independently of the slider. Such prior constructions usually have more fastener elements on one stringer than on the other and one top stop on the longest stringer, together with some means to prevent unlocking movement of the slider or necessitating an extra operation in order to utilize the quick release feature embodied in the fastener. In some of these prior constructions it was also necessary to cut away a portion of the corded edge of the shorter stringer in order to operate properly the quick release feature incorporated therein. Such cutting away of the cord however, requires an additional operation in the manufacture of the fastener and considerable losses have been incurred in the practice of the same.

The primary purpose of the present invention is to provide a novel and improved form of quick release which is free of the disadvantages of prior devices of the indicated type and which will have an appearance similar to that of the ordinary fastener.

A further object of the invention is to provide a fastener which is provided with balanced top stops and which can be opened independently of the slider without changing the position of the latter and while the slider is in a locked condition on the fastener.

Other objects of the invention as well as the advantages and novel features of construction thereof, will become apparent after a perusal of the following description when read in connection with the accompanying drawings, in which Fig. 1 is a front elevational, broken view, of a separable fastener embodying the invention and showing the stringers disconnected from the slider to enable quick separation; Fig. 2 is a front elevational view of the upper portion of the fastener in normal, locked condition; Fig. 3 is a plan view of the blank from which the quick release member is formed; Fig. 4 is an end elevational view of

2

the portion of the stringer on which the quick release member is mounted; Fig. 5 is a front elevational view of the parts shown in Fig. 4, and Fig. 6 is a sectional view taken along the line 6—6 of Fig. 5 and showing in addition, a transverse sectional view of the slider.

In the drawings, the reference numerals 10 and 11 indicate the usual flexible fastener stringers which are to be attached to a garment or article and which have corded or beaded edges 12, 13, respectively, carrying the opposed series of fastener elements 14 and 15, respectively. The opposed series of fastener elements 14 and 15 are moved into engaging interlocking relation in the usual manner by means of a slider 16 of any appropriate construction having convergent guide channels and provided with a hand manipulatable actuating member or pull tab 17. The pull tab 17 may be provided with a locking pin 18 which is arranged to enter into an opening 19 provided on the front or top plate of the slider and into engagement with the series of fastener elements 14 when the pull tab is moved to the position shown in Fig. 2 of the drawings, to lock the slider 16 in position on the stringers 10 and 11. The lower ends of the stringers 10 and 11 carry the cooperating end or bottom stop members 20 and 21, respectively; the stop member 20 being a socket member secured to the stringer 10, and the member 21 being a pin member secured to the corded edge 13 of the stringer 11. The pin member 21 is adapted to be inserted into the upper end of the socket member 20 and when it is properly positioned in the latter, the fastener elements will be in proper relation to be interengaged by the slider 16. When the slider 16 is moved to a position in abutting relation with the upper end of socket 20, the stringers may readily be disconnected in the usual manner by removing the pin 21 from socket 20.

The upper ends of the stringers 10 and 11 carry the top stop members 22, 23, respectively, of the fastener. It will be noted in Figs. 1 and 2 of the drawings, that the top stop members 22, 23 are equidistant from the bottom stop members 20 and 21 so that they may be termed balanced top stops. The stop members 22 and 23 are of similar construction, being substantially U-shaped and being firmly clinched to the stringers 10 and 11, respectively. Stop member 22, like the fastener elements 14, is firmly anchored to the beaded edge 12 of stringer 10, being spaced above the topmost element in such series, a distance approximately equal to the space between adjacent individual elements in the series. The series of fastener elements 15 on stringer 11 is shorter in length than the series of fastener elements 14 so that the stop member 23 connected to stringer 11 is spaced above the topmost element in the series of elements 15, a distance substantially equal to the

longitudinal length of slider 16, as can be seen in Figs. 1 and 2 of the drawings. Spanning the space between the top end of the series of fastener elements 15 and the top stop 23, is a quick release member which is designated generally by the numeral 24.

As is shown in Fig. 3 of the drawings, the release member 24 is made from a flat blank 25 of metal which is approximately .007 inch thick and provided at its lower end with a rectangularly-shaped opening 26 forming a strap 27 having a width substantially equal to the width of the space between adjacent elements 15 on the stringer 11. Intermediate the opening 26 and the longitudinal edges of the blank are a pair of apertures 28, 28 which in the finished form of the member are aligned. The upper end of the blank 25 is provided with a centrally located cutout 29 which in the finished form of the member is concealed by the top stop 23. In forming the release member 24, the blank 25 is shaped along its longitudinal central portion to provide a longitudinal, tube-like section 30 which encloses the corded or beaded edge 13 of the stringer 11 and two longitudinal edge portions 31, 31; the longitudinal portions of such section 30 adjacent to the edge portion 31, 31 converging toward the latter (note Fig. 6). It will be noted from Fig. 5 of the drawings, that when the release member 24 is assembled on stringer 11 with the edge portions 31, 31 thereof located on opposite sides of such stringer, the strap portion 27 of such member will enclose the portion of the corded edge 13 which is intermediate the two uppermost fastener elements in the series of elements 15, while the tube-like section 30 thereof will enclose the corded edge above the topmost element 15 in such series. The cutout 29 at the top of release member 24 will expose sufficient of the corded edge 13 to enable the top stop 23 to be clamped to both such corded edge and the upper ends of the edge portions 31, 31 of the release member. The edge portions 31, 31 of such member is also secured together and to the stringer 11 by means of a rivet 32 which passes through the apertures 28, 28 of such member and through the material of stringer 11. It will thus be seen that the release member 24 is firmly and permanently mounted on stringer 11 by the locking of strap 27 to the topmost fastener element 15, the rivet 32 and the clamping action of the top stop 23.

As is clearly shown in Figs. 1, 5 and 6 of the drawings, in the assembled condition of the release member 24, the tube-like section 30 thereof including the strap portion 27, will be in alignment with the root or anchoring portions 15' of the fastener elements 15 and will closely engage the corded edge 13 of the stringer 11. The tube-like section 30 has a transverse width less than the transverse width of the element anchoring portions 15', but slightly greater than the width of the space between the opposed side flanges 33, 34, on the front and rear plates 35 and 36, respectively, of the slider 16 (note Fig. 6). Thus, for a predetermined size of fastener, if the width of the space between the outer side guides or flanges of the slider is of the order of forty-seven thousandths of an inch, the transverse width of the tube-like portion 30 may be made approximately eighty-five thousandths of an inch. It will thus be seen that as the slider 16 is moved upwardly towards the top stops 22, 23, the two side flanges 33, 34, on the right-hand side of the slider, as viewed in Figs. 1 and 6, will readily pass from

their engagement with the rear edges of the root portions of the fastener elements and onto the longitudinal edge portions of the release member 24 adjacent to the inner longitudinal edges of the tube-like section 30. The width of section 30 being greater than the space between such side flanges 33, 34, the slider will maintain the two upper ends of the stringers 10 and 11 in proper relation. However, should it be desired to pass the tube-like section 30 between such side flanges 33, 34 of the slider, this can readily be accomplished by exerting an outwardly directed force on the member 24. Under such outward force, the inclined or carrying longitudinal portions of section 30 adjacent to the edge portions 31 thereof, will force said slider flanges 33, 34 apart; the plates 35 and 36 of the slider 16 yielding to permit this action to take place. As soon as the tube-like section 30 has passed between the slider flanges 33, 34, the inherent resiliency in the connection of such plates will return the latter and such flanges 33, 34 to their normal positions.

It is believed that an understanding of the operation of the fastener of this invention will be apparent from the foregoing, but for the sake of clearness, it might be pointed out that when the slider is in its uppermost position on the fastener, the latter will be fully closed and the stringers will be retained in proper relation to each other by the coaction of the side flanges 33, 34 of the slider with the rear edges of the elements 14 on stringer 10 and with the tube-like section 30 of the release member 24 on stringer 11. In this position of the slider, the side flanges 33, 34 on the right-hand side thereof, as viewed in Figs. 1 and 6, will be positioned between the topmost fastener element 15 and the top stop 23. The slider may be locked in this position by moving the pull tab 17 to the position shown in Fig. 2 of the drawings, to cause the locking pin 18 thereon to engage between the fastener elements 14 at the top of stringer 10. Should it thereupon be desired to disengage the stringers in the usual fashion, all that is necessary, is to lift the pull tab and manually move the slider downwardly on the series of elements 14 and 15, until it engages the bottom stop, whereupon, the pin 21 of the latter may be withdrawn from the socket 20 thereof to separate the stringers. When the stringers 10 and 11 are so separated, the slider 16 remains connected to stringer 10. On the other hand, should it be desired to separate the stringers 10 and 11, in less time than it would take to operate the slider in the usual fashion, all that is necessary, is to make a slidewise, outward pull on stringer 11, while stringer 10 is being held in the region of or above the release member 24 without moving slider 16 or changing its locked condition in stringer 10. The result of such outward pull will cause the tube-like section 30 of the release member 24 to pass between the associated slider flanges 33 and 34 in the manner previously explained so that such member becomes free of the slider, as is shown in Fig. 1 of the drawings. By continuing such outward pull, the fastener elements 14 and 15 will easily disengage down to the bottom stop and the pin 21 will readily lift out of the socket 20 to completely separate the stringers.

It will be seen from the foregoing, that in appearance, the fastener of the instant invention resembles the usual fastener and is decidedly better looking than the fasteners which have heretofore been provided with quick release means. Such means of the instant invention is

simple in construction, does not require any special manipulation to accomplish the quick release of the stringers and will function in a reliable manner with relatively little effort on the part of the user.

While I have illustrated and described a preferred form of the invention, it will be evident to those skilled in the art, that various changes and modifications may be made therein without departing from the spirit of the invention, or the scope of the appended claims. Thus, for example, it is quite obvious that the invention can be utilized to equal advantage with other forms of fasteners and sliders and that the release member and top stop 23 can be integrally formed instead of being made of separate parts. Also, the release member may be securely anchored to the stringer in some other suitable manner than that specifically disclosed.

I claim:

1. In a fastener including a pair of stringer tapes having reenforced thickened edges with rows of cooperating fastener elements attached to such reenforced edges and a slider movable longitudinally of said stringers to interlock and disengage said elements, said slider comprising a pair of spaced, resiliently supported, plates having marginal side flanges defining a fastener element guide channel and adjacent flanges being spaced for passage of said stringer tapes therebetween, a metal plate folded about the reenforced edge portion for a distance greater adjacent to the upper end of the row of elements thereon, said plate having a cut-out at its upper end so that the longitudinally folded central portion thereof is shorter than the overall length of said plate, said central portion being substantially tube-shaped and snugly enclosing such reenforced edge portion for a distance greater than the length of a side flange of said slider, said tube-shaped portion being of substantially uniform cross-sectional area throughout its entire length, being substantially rigid and non-compressible, and having a transverse outside dimension greater than the normal space between adjacent side flanges of said slider and such that it can be passed laterally through such space as such adjacent side flanges are spread when a sidewise force is exerted on such stringer sufficient to cause such spreading action through said tube-shaped portion, the outer edges of said tube-shaped portion being disposed in converging relation, the portions of said plate beyond said tube-shaped portion being substantially flat and parallelly disposed and integrally connected along the major portions of their inner edges to the converging outer edges of said tube-like portion, the upper ends of said flat plate portions projecting above the upper end of said tube-like portion, an end stop for abutting said slider to limit movement thereof in the closing direction located adjacent to the upper end of said tube-like portion and overlapping the upper projecting ends of said flat plate portions, said end stop including a pair of jaws clamped to the reenforced edge of the stringer adjacently above said tube-like portion and to the upper projecting ends of said flat portions, and means adjacent to the lower end of said tube-like portion securing the lower ends of said flat portions to the material of said stringer.

2. In a fastener including a pair of stringer tapes having reenforced thickened edges with

rows of cooperating fastener elements attached to such reenforced edges and a slider movable longitudinally of said stringers to interlock and disengage said elements, said slider comprising a pair of spaced, resiliently supported, plates having marginal side flanges defining a fastener element guide channel and adjacent flanges being spaced for passage of said stringer tapes therebetween, a top stop on each of said stringers and adapted to abut said slider to limit movement thereof in the closing direction, said top stops being spaced equal distances from the bottom of the fastener and one of said top stops being located adjacent to the upper end of its associated row of elements and the other of said top stops being located at a substantial distance above the upper end of its associated row of elements, a metal plate folded about the reenforced edge portion of the stringer between said other top stop and the upper end of the associated row of elements, said plate having a cut-out at its upper end so that the longitudinally folded central portion thereof is shorter than the overall length of said plate and said central portion having a transverse slot spaced from its lower end and receiving the uppermost fastener member on such stringer, said central portion being substantially tube-shaped throughout its entire length and snugly enclosing such reenforced edge portion both below and above such uppermost fastener element and for a distance above the latter greater than the length of a side flange of said slider, said tube-shaped portion being of substantially uniform cross-sectional area throughout its entire length, being substantially rigid and non-compressible, and having a transverse outside dimension greater than the normal space between adjacent side flanges of said slider and such that above said uppermost element it can be passed laterally through such space as such adjacent side flanges are spread when a sidewise force is exerted on such stringer sufficient to cause such spreading action through such tube-shaped portion, the outer edges of said tube-shaped portion being disposed in converging relation, the portions of said plate beyond said tube-shaped portion being substantially flat and parallelly disposed and integrally connected along the major portions of their inner edges to the converging outer edges of said tube-like portion, the upper ends of said flat plate portions projecting above the upper end of said tube-like portion and underlying said other end stop, said other end stop including a pair of jaws clamped to the reenforced edge of the stringer adjacently above said tube-like portion and to the upper projecting ends of said flat portions, and means adjacent to the lower end of said tube-like portion securing the lower ends of said flat portions to the material of said stringers.
